UNITED STATES PATENT OFFICE.

JOHN J. COMER, OF CHICAGO, ILLINOIS, ASSIGNOR TO AUTOMATIC ENUNCIATOR COMPANY, OF CHICAGO, ILLINOIS, A CORPORATION OF ILLINOIS.

LOUD-SPEAKING TELEPHONE SYSTEM.

1,234,134.

Specification of Letters Patent. Patented July 24, 1917.

Application filed July 21, 1913. Serial No. 780,118.

To all whom it may concern:

Be it known that I, JOHN J. COMER, a citizen of the United States of America, and resident of Chicago, Cook county, Illinois, have invented a certain new and useful Improvement in Loud-Speaking Telephone Systems, of which the following is a specification.

My invention relates to improvements in telephone systems, and more particularly to enunciating or music transmitting systems.

The object of my invention is to provide a system in which a highly increased efficiency of transmission is obtained, and one in which a plurality of transmitters can energize a maximum number of loud speaking receivers.

A further object is to provide means whereby the receivers can be energized either from voice transmitters or from transmitters energized from a sound record.

These and other objects of my invention will be more readily understood by having reference to the accompanying drawings, in which I have shown in diagrammatic form one embodiment of my invention.

I have there shown a battery B, to which are connected the line conductors 2-3, across which are a plurality of bridges each 30 containing a microphone transmitter K and a fixed resistance 4 illustrated in the form of an incandescent lamp. In each of these bridges, it will be noticed that the points 5-6 at which the bridges connect with the line conductors 2-3 being permanently connected to opposite poles of the battery B, remain at substantially a constant potential. When one of the transmitters K is operated, its resistance varies. When the resistance 40 is increased, the drop of potential between the points 5 and 7 is increased, and when the resistance of the transmitter is decreased the potential at 7 is correspondingly changed. We thus have in each bridge the 45 two points, 5 and 6, of constant potential, and the point 7, between the fixed resistance 4 and the transmitter K, of a varying potential, the variation in this potential being proportionate to the variations and resistances of the transmitter K.

From this it will be seen that the variation of potential between the points 6 and 7 is similar to and proportionate to the variation between the points 5 and 6—that is, 55 when the transmitter K is operated, if a re-

ceiver were connected across the points 6 and 7, it would be operated in the same manner as if a receiver were connected across the transmitter itself at the points 5 and 7. To make use of this feature, I provide 60 a plurality of transmitting circuits M, one around each of the transmitters K and likewise around each of the fixed resistances 4. In this manner I provide twice as many receiving circuits as there are microphone 65 transmitters K, and each one of these receiving circuits is adapted to energize a plurality of repeaters or amplifiers R, which repeaters in turn energize a plurality of loud speaking receivers Z.

These amplifiers can be of any desired type, and I have illustrated same as comprising a magnet 8, a differential microphone transmitter 9, the armature of the magnet being connected to the movable electrode in the transmitter through the system of levers 10. A loud speaking receiver Z is connected in the local circuit with this transmitter and the battery B' in the manner well understood in the art. As this does 70 not form part of my present invention, it is not thought necessary to describe same more in detail.

At Y, I have indicated diagrammatically an apparatus for receiving vibrations from 85 a record, and when it is desired to energize certain of the loud speaking receivers Z from this source, instead of from one of the microphones K, I have provided a pair of switches X-Y' whereby by closing the 90 switch Y' and opening X, the transmitter K is cut off from the reproducing circuit and the transmitter Y connected thereto. In a similar manner, when the switch Y' is 95 open and the switch X closed, the reproducing circuit is energized from the transmitters K.

It will thus be seen that I have devised a very efficient form of telephone system in which the fixed resistance connected in series 100 with the transmitters K are just as effective in varying the potential in their respective receiving circuit M, as are the transmitters themselves. In this manner I am able to energize twice as many receiving circuits as 105 there are microphone transmitters.

While I have illustrated and described one embodiment of my invention in connection with an apparatus of a particular type, it is, of course, understood that I do not wish 110

to limit myself to the exact construction shown and described, and that various changes and modifications can be made without departing from the spirit of my invention.

5. What I claim as my invention is:

1. In a telephone system, a battery, a variable resistance transmitter and a fixed resistance connected in series, a receiving circuit 10 connected directly around said transmitter, and a second receiving circuit connected directly around said fixed resistance.
2. In a telephone system, a battery, a pair of line conductors connected to opposite poles of the battery, a plurality of bridges across said line circuit, each of said bridges including a variable resistance transmitter and a fixed resistance connected in series, a receiving circuit connected directly around 15 each of said transmitters, and a second receiving circuit connected directly around each of said fixed resistances.
3. In a telephone system, a battery, a variable resistance transmitter and a fixed resistance connected in series, a receiving circuit 20 connected around said fixed resistance and excluding said transmitter, one or more amplifiers bridged across said receiving circuit, and one or more loud speaking receivers 25 operatively connected with each of said amplifiers.
4. In a telephone system, a battery, a variable resistance transmitter and a fixed resistance connected in series, a receiving circuit 30 connected directly around said transmitter,

a second receiving circuit connected directly around said fixed resistance, one or more amplifiers bridged across each of said receiving circuits, and one or more loud speaking receivers operatively connected with each of 40 said amplifiers.

5. In a telephone system, a battery, a pair of line conductors connected to opposite poles of the battery, a plurality of bridges across said line circuit, each of said bridges including a variable resistance transmitter and a fixed resistance connected in series, a receiving circuit connected directly around each of said transmitters, a second receiving circuit connected directly around each of 45 said fixed resistances, one or more amplifiers bridged across each of said receiving circuits, and one or more loud speaking receivers operatively connected with each of said amplifiers.

6. In a telephone system, a microphone transmitter adapted to be energized directly by voice currents, a second transmitting apparatus adapted to be operated by vibrations received from a record, a receiving circuit, 50 loud speaking receivers operatively connected to said receiving circuit, and means for connecting either one of said transmitters to said receiving circuit.

Signed by me at Chicago, Illinois, this 65
18th day of July, 1913.

JOHN J. COMER.
